UNITED STATES PATENT OFFICE.

SAMUEL V. RAWLINGS, OF MARQUETTE, MICHIGAN, ASSIGNOR OF ONE-HALF TO SEYMOUR H. HOLLEY, OF SAME PLACE.

SAW-SWAGE.

SPECIFICATION forming part of Letters Patent No. 593,782, dated November 16, 1897.

Application filed June 26, 1896. Serial No. 596,989. (No model.)

To all whom it may concern:

Be it known that I, SAMUEL V. RAWLINGS, a citizen of the United States, and a resident of the city and county of Marquette, in the 5 State of Michigan, have invented certain new and useful Improvements in Saw-Swages, of which I do declare the following to be a full, clear, and exact description, reference being had to the accompanying drawings, forming 10 a part of this specification.

The present invention has for its object more particularly to provide an improved construction of saw-swage especially adapted for the swaging of that type of saws having 15 round interdental throats and chisel-pointed teeth. In swaging saw-teeth it is of the utmost importance that the original shape of the teeth should be preserved. With saw-teeth of ordinary construction this is readily 20 accomplished by various kinds of swages, and particularly by that class of swages that spread the metal upon the under side of the points of the teeth. Where attempt has been made, however, to use this kind of saw-swage 25 upon the type of saws above mentioned, it has been found in practice that the shape of the tooth is speedily destroyed and the saw thereby rendered unfit for use. In swaging such type of saw-tooth resort has heretofore 30 been had to swages in which a depression of the metal at the top or crown of the tooth is made, and during such depression of the metal at the top or crown the under side of the tooth-point has been supported by a die, 35 serving to rigidly retain or preserve the original shape of the throat between the teeth. It has been found, however, that in the use of such prior type of swage the depression of the crown of the tooth spreads the metal so 40 abruptly at the top of the tooth-crown that its effect upon the lumber is to mar the same, so that this method of swaging has also met with disfavor.

By my present invention I provide a swage 45 whereby the original shape of the tooth may be preserved and whereby the abrupt lateral expansion of the metal may be avoided, and instead of such abrupt lateral expansion a gradual lateral expansion of the metal may 50 be had, so that the desired "chisel-shaped"

outline in cross-section shall be given to the tooth.

The leading feature of my present invention consists in first depressing or swaging downward the crown of the tooth, and thereafter swaging upward from the bottom or under side of the tooth the material that had been pressed down from the top, so that the original diameter of the interdental throat is preserved and the desired chisel-shaped out- 55 line is given to the teeth. 60

My invention also consists in the various novel features of construction hereinafter described, illustrated in the accompanying drawings, and particularly defined in the 65 claims at the end of this specification.

Figure 1 is a view in side elevation of my improved saw-swage. Fig. 2 is a view in vertical longitudinal section, parts being shown in elevation, the section being taken at one 70 side of the center. Fig. 3 is a plan view. Fig. 4 is a view in side elevation from the opposite side of the swage shown in Fig. 1. Fig. 5 is a view in vertical cross-section on line 5 5 of Fig. 3. Fig. 6 is a detail end view of the tail-piece, its support being shown in vertical section. Fig. 7 is a detail end view of the head-piece. Fig. 8 is a detail view, in front elevation, of the lever that operates the anvil-block. Fig. 9 is a detail view, in front elevation, of the 75 anvil-block. Fig. 10 is a detail view of the die-carrying roller. Fig. 11 is an end view of a die-carrying roller. Fig. 12 is a view in cross-section on line 12 12 of Fig. 10. Fig. 13 is a view showing the right-hand end of the 80 die-carrying roller. 85

The body of the swage is shown as consisting of side portions A and A', that are united together by cross-webs a, a', and a'', (see Figs. 2 and 5,) it being understood, of course, that 90 these parts will be formed preferably of a single casting. Between the depending parts of the side portions A and A' is formed the open space a³, in which the saw-blade X will be held during the swaging operation. In the 95 side portion A' of the swage-body is formed a threaded perforation to receive the screw B, and at the opposite point of the portion A is formed a like threaded perforation to receive the screw-threaded shaft B', the outer end of 100

which has fixed thereto the handle B². The screw B and the screw-shaft B' serve to firmly hold the saw-blade in position during the swaging operation by firmly clamping the opposite 5 sides of the blade, as shown in Fig. 5, and by preference a set-screw b, that passes through a correspondingly-threaded hole in the side portion A' of the swage-body, serves to hold the screw B with accuracy in any position at 10 which said screw B may be set. Through the depending portions A and A' of the swage-body is formed a transverse circular opening to receive the die-carrying roller C, the preferred form of which is more fully illustrated 15 in Figs. 10 to 13 of the drawings. One end of this roller C is of polygonal outline, as shown in c, and has fixed thereto the operating-handle C', and through the opposite end of the roller C is formed a circular hole or seat 20 to receive the roller-die C² and its retaining-pin s. The roller-die C² is shown of a length equal to the space between the sides A and A' of the swage, although, if desired, it can be the full length of the hole formed in the 25 roller C, in which event the retaining-pin s need not be used. The die-carrying roller C is shown as formed with the annular groove c' adjacent one end, into which will set the yoke-shaped end of a retaining-plate 2, that 30 is held in position by means of a set-screw 3, (see Fig. 4,) and in order to retain the roller-die C² in place within the roller C a plate 4 is attached to the side of the swage-body by means of a set-screw 5. (See Fig. 5.)

35 The die-carrying roller C, as seen in Figs. 2, 5, and 10, is shown as cut away, as at c², about its center, leaving the raised or eccentric portions c³ at each side of the central cut-away space c², and, as seen in Fig. 12, these 40 raised portions c³, which are shown as of the same radius as the body of the roller C, extend about one-third of the periphery of the roller—that is to say, from the point 6 to the point 7. The periphery of the roller C, as 45 will be seen by Figs. 10 and 12, is cut away in the plane of the raised portion c³ from the points 6 and 7 downward, leaving the raised portion c⁴ and leaving the flattened or cut-away spaces c⁵ and c⁶. Into the cut-away 50 spaces c⁶ extend the bifurcated end portions d of the lever D, (see Fig. 2,) that is journaled upon a pin 8, that passes through the body of the swage. The lever D is an elbow-lever, and in its upper end is formed a threaded 55 hole to receive an adjusting-screw D', that is fitted preferably with a jam-nut D². The purpose of the screw D' is to determine with accuracy the extent of movement of the anvil E, that is mounted within a suitable seat or 60 channel formed in the body of the swage, as shown in Fig. 2. The adjusting-screw D' also serves to take up any lost motion incident to imperfect fit of the parts or incident to wear from usage. This anvil E (see Fig. 65 2) has its lower end preferably formed with two tips e, either of which may be used to give the proper swaging action upon the saw-

tooth, it being understood, of course, that when one of the tips e has become worn the anvil E can be reversed, so as to bring the 70 opposite tip into position for use.

From the construction of parts as thus far defined the operation will be seen to be as follows: The saw-blade X will be placed between the screw B and the screw-shaft B' in 75 the position seen in Figs. 2 and 5 of the drawings, at which time the under side of the first tooth-point to be swaged will extend beneath the anvil-tip e and rest upon the curved portion of the roller C at the base of the cut-away space c². (See Figs. 2 and 10.) The handle B² will then be turned so as to cause the screw-shaft B' to firmly clamp the saw-blade in position, and the handle C' will next 80 be turned, so as to cause the die-carrying 85 roller C to revolve in the direction of the arrow, Fig. 2. As the roller C thus revolves the raised portions c³ will bear upon the ends d of the elbow-lever D, thereby causing this lever to rock about its pivot-point and to force 90 downward the anvil E, causing the tip e of the anvil to compress the metal at the top of the saw-tooth. As this compression of the metal begins the flat cut-away space c⁵, that extends above the roller-die C², will come beneath the point of the saw-tooth, so that as the downward movement of the anvil E continues the point of the saw-tooth will be forced downward into this cut-away or flat space c⁵. As the roller C continues to revolve in the 100 direction of the arrow, Fig. 2, the roller-die C² will contact with the under surface of the saw-tooth that has just been depressed and force the same upward, but as the upward movement of the depressed portion of the 105 saw-tooth is resisted by the tip of the anvil E it is obvious that the metal constituting the saw-tooth point will be spread or swaged laterally. It will be observed that the periphery of the roller-die C² is concentric with the 110 portion of the roller C at the base of the cut-away space C². Consequently when the roller-die C² has thus been forced beneath the point of the saw-tooth the interdental throat of the saw-tooth will be restored to its original diameter and shape. This is a feature of the 115 utmost importance, since swages that have been heretofore employed upon saw-teeth of the type shown—that is to say, of the round-point and chisel-pointed type—and in which 120 a swaging of the saw-tooth is effected from the under side, the shape of the tooth has been soon destroyed.

By means of the set-screw D' it will be seen that the position of the anvil E can be readily 125 determined, so as to give any degree of swaging action upon the teeth of the saw.

In order to properly hold the swage in position upon the saw-blade and prevent its 130 tilting back or forth during the swaging operation and in order also to enable the body of the swage to be so adjusted as to vary the angle at which the tip e of the anvil E shall act upon the saw-teeth, I provide the adjust-

able head-block F and tail-block G, these blocks being carried, respectively, by suitable supports F' and G'. The head-block F is adjustably mounted upon its supporting-arm F' and held in any desired position by a set-screw f and jam-nut f', and the support F' (see Fig. 7) has its expanded space formed with the slots f², through which pass the set-screws f³, whereby the support F' can be set at any desired position with respect to the body of the swage. The tail-block or shoe G has its upper portion bifurcated to straddle its support G', to which it is connected by a through-bolt g and nuts g'. The bifurcated ends of the tail-block G are provided with the slots g², and the support G' is provided with the slot g³, through which slots the bolt g passes, and by means of the slots g² and g³ and the bolt g the position of the tail-block G upon its support G' can be shifted, as desired. By reference to Fig. 6 it will be seen that the base of the tail-block support G' is formed with slots g⁴, through which pass the set-screws g⁵, that enter threaded perforations in the body of the swage and serve to permit the adjustment of the support G' in upward or downward direction. It will be observed that the lower end of the tail-block G is bifurcated (see Fig. 6) to straddle the saw-blade, and the tail-block is furnished with a shoe g⁶, of chilled steel, to better resist wear. By adjusting the head-block F its tip f⁴ can be brought to bear upon that part of the crown of the saw-teeth not acted upon by the anvil E, whatever may be the distance between the teeth of the saw.

To one side of the body of the swage is attached a stop-arm T, that is held in place by a set-screw t, this arm being formed with an angular end t', (see Fig. 3,) against which the handle C' will contact and by which its movement will be limited, so that at the beginning of the swaging operation and when the handle C' is resting against the stop-arm T the parts will be in proper relation to receive the teeth of the saw.

My present invention presents the first instance, so far as I am aware, of a saw-swage that is adapted to swage from the bottom or under side of the tooth the material that is pressed down from the top or crown of the tooth, thus avoiding any change in the original outline of the throat of the tooth.

It is manifest that in carrying out the invention the precise details of structure above set forth may be modified within wide limits without departing from the spirit of the invention, and I do not therefore wish the invention to be understood as restricted to such details.

Having thus described my invention, what I claim as new, and desire to secure by Letters Patent, is—

1. A saw-swage comprising the combination of a suitable anvil, means for shifting said anvil to cause it to compress the top of the saw-tooth, a movable die having a reduced or flat-

tened part exposed to the under side of the saw-tooth during the compressive action of the anvil and having a projecting part to engage the under side of the saw-tooth after the top of said tooth has been compressed by the movement of the anvil and swage outward the material pressed down from the top or crown of the tooth, substantially as described. 70 75

2. In a saw-swage the combination of a suitable anvil, means for shifting said anvil to cause it to compress the top of the saw-tooth, a rotary die having a reduced or flattened part exposed to the under side of the saw-tooth 80 during the movement of said anvil and having a projecting part to engage the under side of the saw-tooth after the top of said tooth has been compressed by the anvil and swage outward the material pressed down from the top 85 or crown of the tooth, substantially as described.

3. In a saw-swage the combination of a suitable anvil, means for shifting said anvil to cause it to compress the top of the saw-tooth, 90 a rotary die having a reduced or flattened part exposed to the under side of the saw-tooth during the movement of the anvil and having a projecting part consisting of a roller-die to engage the under side of the saw-tooth 95 after the top of said tooth has been compressed by the anvil and swage outward the material pressed down from the top, substantially as described.

4. The combination of a suitable anvil, a die-carrying roller provided with a roller-die mounted therein, said die-carrying roller being reduced or flattened at one side of the roller-die to permit the metal of the saw-tooth to be depressed by the anvil, and means for shifting said anvil to cause it to compress the top of the saw-tooth before said roller-die is brought into engagement with the under side of said saw-tooth, substantially as described. 100 105

5. In a saw-swage the combination of a suitable anvil, a die-carrying roller having a bearing-surface against which the under side of the saw-tooth will bear when said tooth is first inserted in the swage and having a roller-die projecting from its periphery and having a reduced or flattened portion intermediate said roller-die and said bearing-surface and suitable means for shifting said anvil to cause it to compress the saw-tooth while the end of said tooth is opposite the reduced or flattened 115 portion of the die-carrying roller and before the roller-die is caused to engage the under side of the saw-tooth, substantially as described. 120 110

6. In a saw-swage the combination with a suitable anvil, of a rotary die-carrying roller having a raised or eccentric part and having a suitable part to act upon the under side of the saw-tooth, and a pivoted lever, one arm of which engages the raised or eccentric part of the die-carrying roller and the other arm of which actuates said anvil, substantially as described. 125 130

7. In a saw-swage the combination with a

suitable anvil, of a die-carrying roller having a raised or eccentric part and an elbow-lever intermediate said die-carrying roller and said anvil, one arm of said elbow-lever extending 5 in position to engage said raised or eccentric part of the die-carrying roller, and the opposite arm of said elbow-lever being provided with an adjusting-screw to determine the movement of the anvil, substantially as de-
10 scribed.

8. In a saw-swage the combination with the die-carrying roller C provided with the roller-

die C² and having the cut-away space c² and the raised parts c³, the pivoted elbow-lever D, the lower end whereof engages said roller C, 15 the set-screw D' extending through the upper end of said elbow-lever and the anvil E bearing against said set-screw D', substantially as described.

SAMUEL V. RAWLINGS.
